Primary Examiner—Sandra L. Morris*Attorney, Agent, or Firm*—Collard & Roe, P.C.**[57] CLAIM**

The ornamental design for a multi-level game board, as shown and described.

DESCRIPTION

FIG. 1 is a perspective view of a multi-level game board, showing my new design;

FIG. 2 is a top plan view thereof;

FIG. 3 is a left side elevational view thereof, the right side elevational view being identical; and,

FIG. 4 is a front elevational view thereof, the rear elevational view being a mirror image thereof.
